J. AUGUSTUS LYNCH, OF BOSTON, MASSACHUSETTS, ASSIGNOR TO HIMSELF, R. K. HUNTOON, AND C. S. LYNCH, OF SAME PLACE.

Letters Patent No. 90,371, dated May 25, 1869.

IMPROVEMENT IN STEAM-ENGINE LUBRICATORS.

The Schedule referred to in these Letters Patent and making part of the same.

To all persons to whom these presents may come:

Be it known that I, J. AUGUSTUS LYNCH, of Boston, of the county of Suffolk, and State of Massachusetts, have invented a new and useful Improvement in Lubricators for Steam-Engine Cylinders; and do hereby declare the same to be fully described in the following specification and represented in the accompanying drawings, of which—

Figure 1 is a side elevation, and
Figure 2, a vertical section of it.

In carrying out my invention, I combine with a "globe-valve," a tallow, or lubricating-vessel, and a means of discharging therefrom by and with steam, and into the cylinder or steam-chest of a steam-engine, oil or tallow for the purpose of lubricating the internal surfaces and the piston of such chest and cylinder.

In the drawings—

A denotes a "globe-valve," which consists of a globular case, *a*, a valve, *b*, and mechanism for elevating and depressing the latter relatively to its seat *c*, there being an induction-opening, *d*, and an eduction-passage, *e*, to such case, the whole being as represented, and as ordinarily constructed.

Extending both within and above the valve-case *a*, is a vessel, *B*, or oil or tallow-reservoir, it being provided with a cap or cover, *f*, and also with a mouth, *g*, the latter being to enable the vessel to be supplied with the lubricating-material as occasion may require.

The valve-stem *h* has a screw, *i*, made on it to screw through the bottom of the oil-vessel.

The said bottom is also formed, at its lower part, with a conical valve-seat, *k*, to receive an auxiliary valve, *l*, which is applied to the stem *h*, and above the main valve.

At its upper part, the said stem of the valve is prismatic, and enters a rotary key, applied to the cap of the oil-vessel.

By revolving the said key in either direction, the valve and its stem will be revolved. Therefore, by means of the key, the valve may be raised off its seat or forced down upon the same, as circumstances may require.

The auxiliary valve may also be brought up against its seat, so as to stop the flow of steam through the seat, and the spray-duct applied thereto.

This spray-duct consists of a pipe, *C*, leading laterally out of the auxiliary valve-seat, and provided with one or more lateral passages *m*, extending up from its bore into the oil-chamber or vessel.

This pipe is to lead into that part of the supply-pipe of the steam-chest of the cylinder which extends

from such steam-chest to the valve-seat of the governor, and there may be a stop-cock, *x*, in the spray-duct.

From the above, it will be seen that when the main valve *b*, of the case *a*, is raised off its seat, so as to cause the auxiliary valve *l* to be brought close up to its seat *k*, the passage of steam into and through the spray-duct *C*, will be cut off; also that when the valve *l* is off its seat, the steam, when in the globe-valve case, will have free access to such spray-duct, and will rush through it and draw oil from the oil-reservoir, break up such oil into spray, and discharge it into the steam-chest, from whence it will flow, or be carried into the cylinder, whereby it will be caused to lubricate the valve and the piston of the cylinder.

In that part of the steam-pipe which is between the governor and the steam-chest, the pressure of the steam is much less than it is within the globe or stop-valve case, the same being due to the fact of the steam being more or less throttled by the governor-valve.

Consequently the excess of pressure will cause the steam from the globe or stop-valve case to rush with great velocity into and through the spray-duct, when the auxiliary valve *l* is off its seat.

By having the grease-vessel arranged with the globe-valve, in manner as set forth, the steam, when in or passing through the case of the latter, will heat the grease-vessel, and consequently melt the tallow or grease which may be put therein.

By such arrangement of the grease-receiver, the grease will be melted or tried out by contact with the hot metal.

The auxiliary valve and its seat also operate to pack the valve-stem when the stop-valve is entirely open, or raised to its greatest altitude.

What I claim as my invention may be stated as follows; that is to say—

I claim the combination as well as the arrangement of the grease-vessel *B* with the stop-valve *b*, its case *a*, and stem *h*, substantially as described, such being so that steam, when in the said case, may come into contact with and heat the said grease-vessel.

Also, the combination of the grease-vessel *B*, the spray-duct *C*, one or more passages *m*, and the auxiliary valve-seat *k*, with the stop-valve *b*, its case *a*, and operative mechanism, and with the auxiliary valve *l*, applied to the stem of the said stop-valves, as explained, the whole being substantially as hereinbefore described.

Witnesses: J. AUGUSTUS LYNCH.
